DOUBLE WINDOWPANE

Carl F. Huddle, Ferndale, Mich., assignor to General Motors Corporation, Detroit, Mich., a corporation of Delaware

Application December 9, 1942, Serial No. 468,359

5 Claims. (Cl. 20—56.5)

This invention relates to a multiple window pane structure having a heat insulating space for air or some other medium between the panes.

It relates more specifically to such structures in which the panes are sealed in a frame of metal or the like by some kind of adhesive cement. Such a cement should be strongly adhesive to the materials of the multiple window pane, should have some resilience, be capable of expansion and contraction without destruction of the seal, and should not permit permeation of moisture from the atmosphere into the space between the panes with consequent fogging of the inside surfaces of the panes.

Different kinds of thermoplastic sealing compound have been used but no one of them has all the desirable qualities enumerated above and none is known to the applicant.

Pitch has been used as a sealing compound and has the desirable quality of high resistance to permeation of moisture, but is not a sufficiently good adhesive under all the temperature and pressure conditions encountered. Other substances, which are better adhesives, are unfortunately hygroscopic and permit moisture to permeate to the space between the panes.

The object of the invention is a structure in which the panes are sealed in a frame of metal or the like by multiple means providing in combination the desirable qualities enumerated above.

The above and other objects of the invention will be apparent as the description proceeds.

According to the invention, the spacer between the panes is of resilient material, such as rubber, which is held under compression therebetween by the frame of the multiple window pane. The spacer is inset from the edges of the panes to provide a space for a vapor dam of pitch which is preferably semi-plastic or even semi-liquid throughout the temperature range likely to be encountered and is confined between the spacer, the panes and the frame, which frame is secured over the edges of the panes by a strong adhesive. With this construction there can be no infiltration of water vapor to the space between the panes even though the adhesive is hygroscopic.

The drawing shows three different modifications of a structure according to the invention.

In the drawing:

Figure 1 is a perspective view of a completed double window pane structure.

Figure 2 is an enlarged sectional view on line 2—2 of Figure 1.

Figure 3 is an enlarged sectional view showing a modification.

Figure 4 is an enlarged sectional view showing another modification.

5 Referring now to Figures 1 and 2, the panes 1 and 2 of glass or other transparent material are held in separated relationship by a spacer, in a frame of suitable strip material rolled to the section shown in Figure 2.

10 The spacer consists of two hollow resilient tubes 4 and 5 of rubber or the like, bonded to opposite sides of metal strip material 7. The metal strip 7 gives the spacer some rigidity so that it may be readily laid straight and parallel to the edges of the panes from which it is inset.

The spacer is secured in position in compression between the panes, and between the spacer and the edges of the panes there is provided a space for a vapor dam 18 of plastic material such as pitch which is impermeable by water vapor.

15 A proper amount of pitch having been inserted in this space, the frame in the form of strip material notched at intervals as shown in broken lines in Figure 1, so that it may be bent to form side members 13 and 14 and end members 15 and 16 with mitered ends and with a layer 18 of good adhesive over its inner surface, is pressed over the edges of the panes with the resilient spacer held under compression by the side walls of the frame.

20 The butt joint 20 between the ends of the strip forming the frame is preferably arranged to be at about the middle of one of the sides as shown in Figure 1.

25 It will be noted that by this construction the resilient spacer provides a seal with the requisite resilience, the pitch provides an effective vapor dam between the space between the panes and the outside atmosphere and is confined to the space provided for it by the stronger adhesive, while it is at the same time protected by the stronger adhesive from contact with any undesirable solvents thereof such as the oil in glazing putty.

30 The embodiment shown in Figure 3 is similar to that shown in Figures 1 and 2 except that the rubber 20' of the spacer is solid instead of tubular.

In Figure 4 the metal frame 24 has a resilient cross section provided by the corrugations 21, while the use of a hollow resilient spacer 26 of square cross section and without metal reinforcement is shown. The resilient frame permits of a greater degree of differential expansion between the panes and can be used when the differential pressure and temperature conditions are such as

to require a greater resilience in the frame. The corrugations which provide the requisite transverse flexibility at the same time provide a longitudinal stiffness which is desirable in the frames of larger window panes. A suitable material for the frame is a thin soft metal such as copper, but it will be appreciated that other materials (e. g., various kinds of plastic material or rubber) might be used.

I claim:

1. A multiple window pane structure having a frame of strip material for its edges, a resilient spacer between the panes and spaced from the frame, a water vapor dam of plastic material impervious to moisture in the space thus provided between said spacer, said panes and said frame, and a less impervious but stronger adhesive

between said panes and said frame, to bond the parts together.

2. The combination according to claim 1, in which the resilient spacer is held under compression between the panes, by the frame.

3. The combination according to claim 1 in which the spacer consists of resilient material bonded to a metal strip.

4. The combination according to claim 1 in which the spacer is formed of tubular resilient material.

5. The combination according to claim 1 in which the frame consists of a single strip of suitable material bent around the perimeter of the panes, and with a butt joint between its ends at about the middle of one side.

CARL F. HUDDLE.
